F. M. COFFIN

SAFETY ELEVATOR INTERLOCK

Filed April 23, 1921

Inventor

By his Attorney *Frank M. Coffin*
Wm Wallace White

UNITED STATES PATENT OFFICE.

FRANK M. COFFIN, OF PELHAM, NEW YORK.

SAFETY ELEVATOR INTERLOCK.

Application filed April 23, 1921. Serial No. 463,746.

To all whom it may concern:

Be it known that I, FRANK M. COFFIN, a citizen of the United States, residing at Pelham, New York, have invented new and 5 useful Improvements in Safety Elevator Interlocks, of which the following is a specification.

This invention relates to improvements in safety devices for elevators, the object 10 of the invention being to provide an improved device which is automatically operative to prevent opening of the doors while the elevator is in motion and which may be applied to elevator systems having 15 any form of car operating means.

A further object of the invention is the provision of a device of the character set forth by means of which, when the car is at rest in the proper position in front of 20 the landing, the door may be opened either from the landing or from within the car.

A further object of the invention is to provide a device of the character set forth in which a plurality of selector switches 25 are employed for releasing the door locking means, and which switches are preferably operated by the car itself, whereby the doors cannot be opened until the car is at rest opposite the door opening.

With the foregoing and other objects in view, which will appear as the description proceeds, the invention consists in the novel features of construction and combination of parts which will be more fully described hereinafter and particularly pointed 35 out in the claims.

The drawing accompanying and forming part of this specification is a diagrammatic side elevation of a preferred embodiment 40 of the invention applied to an electrically operated elevator.

Referring to the drawing, 2 designates the wall of an elevator shaft, which is illustrated as having four landings, 3, 4, 5 and 45 6 respectively. Each of the four landing doors (not shown) is equipped with a suitable electro-mechanical lock. As the lock itself, however, forms no part of the present invention, I have, for the sake of clear- 50 ness, omitted the details thereof and have illustrated only an electro-magnetic coil 7 for each door lock.

In the form of the device illustrated herein, each of the coils 7 is adapted to be 55 electrically connected by means of wires 8 and 9 with main line conductors 10 and 11,

respectively, leading to a source of electrical energy, said conductors being also connected with the terminals of a motor M which may be used for operating the car in any well-known manner.

On the elevator control board (not shown), the conductor 11 and wire 9 run parallel, and are each separated to form a gap, a bridging contact being provided for closing the circuit across said gaps. This bridging contact comprises an electromagnet having a core 15 provided at each end thereof with a bridge piece 16 and 17, adapted to bridge the gaps in the conductor 11 and wire 9 respectively. For energizing the core, a coil 12 is provided having lead wires 13 and 14 by which the coil may be connected to the main line conductors, or to any other suitable source of energy, such as for instance as a battery. The wires 13 and 14 will include in their circuit any suitable form of elevator operating and controlling switch, such for instance as the switch 22, which may be located either in the car itself or one of such switches located at each landing and adapted to be operated by a push-button, in the usual manner. These devices are all well-known in the art, and therefore it is deemed unnecessary to describe them in detail.

Mounted in the elevator shaft or hatchway, opposite each of the doors, is an electric switch 18 adapted to normally maintain the circuit to the coils 7 open, as shown at the uppermost and the two lower landings. These switches may be held open either by springs (not shown) or by means of gravity, and are each provided with a roller 19 adapted to contact with a cam 20 of any suitable material and form, carried by the car 21, shown in dotted lines, for operating the switches into circuit closing position, as shown at the third landing illustrated in the drawing, as soon as the car has arrived at its proper position in front of the landing.

The operation of the device will be obvious from the foregoing description taken in connection with the drawing. The switches 18 are normally retained in circuit-breaking position, and the doors at the various landings locked. Assuming the car to be at rest, the core of the electromagnet A will have fallen by gravity so that its bridge piece 17 contacts with the terminals of the wire 9, whereby the bridge piece 16

is moved away from the terminals of the conductor 11 so that the motor is inoperative. If it is desired to operate the car, the usual lever within the car, or a push button at one of the landings, is operated to throw the car-operating switch 22 into circuit-closing position, which closes the circuit through the coil of the electromagnet A and thus energizes the core 15, which moves upward until its bridge piece 16 contacts with the terminals of the conductor 11, thus opening the circuit to the coils 7 and closing the circuit to the motor, whereby the car will be raised or lowered to the desired landing. On its arrival there, the cam 20 will have thrown the switch 18 at that landing into circuit closing position, but owing to the fact that the circuit is broken by the removal of the bridge piece 17 from contact with the terminals of the wire 9, no current can pass through the coil 7 until the switch 22 has been opened to open the circuit to the motor. When the lever or push button has been operated into circuit-breaking position, current will cease to pass through the coil of the electromagnet A, which thus becomes deenergized and the core 15 falls by gravity until its bridge piece 17 again contacts with the terminals of the wire 9, while the bridge piece 16 has moved away from the terminals of the conductor 11 and thus broken the circuit through the motor so that the car stops. It will be obvious that with the bridging piece 17 in contact with the terminals of the wire 9 the circuit will be closed to the coil 7 at the particular landing where the car has stopped, whereby the core of the solenoid, or the keeper of the electromagnet at that landing will be energized thereby to withdraw the lock from the door and permit the same to be opened either from the landing or from within the car. It will thus be obvious that, although the switches 18 are successively operated every time the car travels up or down the shaft, it will be impossible for the doors to be opened while the car is moving and therefore the moment the car starts to move from rest the door which has been unlocked automatically becomes locked, because the circuit through the coils 7 is open as long as the electromagnet A is energized, and when said magnet is deenergized, the circuit through the motor is opened by reason of the falling of the bridge piece 16 from the terminals of the conductor 11.

While I have for purposes of illustration shown my safety device in connection with an electrically operated elevator, I desire it distinctly understood that my invention is not limited to such application, as I am well aware that the device is capable of other applications and that many mechanical changes and modifications may be made in

the details of construction without departing from the spirit and scope of the invention as set forth in the claims appended hereto.

Having thus described my invention, what I claim is:

1. The combination with an elevator having doors normally retained in locked position and means for actuating the elevator, of electrically operated means for unlocking said doors, and an electromagnet having a circuit-closing member in the circuit of said unlocking means, said electromagnet being adapted to be energized when the elevator-actuating means is operated, thereby to open said circuit. 75

2. The combination with an elevator having doors normally retained in locked position and means for actuating said elevator, of electrically operated means for unlocking said doors, an electromagnet having a pair of circuit-closing elements one effective to close a circuit through said elevator-actuating means and the other to close a circuit through said unlocking means, and means for energizing said electromagnet thereby to open one circuit and close the other. 80 85

3. The combination with an elevator having doors normally retained in locked position and means for operating the elevator, of an electromagnet associated with each of said doors for withdrawing the locks therefrom, said electromagnets being electrically connected with a source of energy, a circuit closing device in the circuit of each of said electromagnets and operable to close said circuit during movement of the elevator, and a second circuit controlling device in said circuit automatically operative to retain the circuit open while the elevator is moving. 90 95 100

4. The combination with an elevator having doors normally retained in locked position and means for operating the elevator, of an electromagnetically operated member associated with each of said doors for withdrawing the locks therefrom, said electromagnetically operated members being connected with a source of electrical energy, a circuit-controlling device in the circuit of each of said members and operable by the passage of the car to close said circuit, and a second circuit-controlling device in said circuit and automatically operative upon actuation of said elevator-operating means to open said circuit. 110 115 120

5. The combination with an elevator having doors normally retained in locked position and means for operating the elevator, of an electromagnet adjacent to each of said doors for unlocking the same, said electromagnets being electrically connected with a source of energy, a circuit-controlling device in the circuit of each of said members and operable to close said circuit during movement of the elevator, an electromagnet 125 130

having a pair of circuit-closing elements one effective to close a circuit through said elevator-operating means and the other to close the circuit through said circuit-controlling devices, said circuit-closing elements being so disposed that one is in circuit-closing position and the other in circuit-breaking position when the electromagnet is energized

and vice versa when the electromagnet is deenergized, and means for closing a circuit through the coil of said electromagnet thereby to energize the same.

In testimony whereof I have signed my name to this specification.

FRANK M. COFFIN.
